UNITED STATES PATENT OFFICE

126,460

DESIGN FOR A TRANSPARENT BRAID OR SIMILAR ARTICLE

Jacob Fishman, New York, N. Y.

Application October 30, 1940, Serial No. 96,190

Term of patent 3½ years

To all whom it may concern:

Be it known that I, Jacob Fishman, a citizen of the United States of America, residing in New York, county of New York and State of New York, have invented a new, original, and ornamental Design for a Transparent Braid or Similar Article, of which the following is a specification, reference being had to the accompanying drawing, forming part thereof.

Fig. 1 is a front view of a transparent braid or similar article showing my new design.

Fig. 2 is a rear view thereof.

Fig. 3 is a side view illustrating the stitched thread.

I claim:

The ornamental design for a transparent braid or similar article, as shown and described.

JACOB FISHMAN.
